RAILWAY REFRIGERATOR CAR

Horace Giddings, San Francisco, Calif.

Application April 17, 1936, Serial No. 74,936

27 Claims. (Cl. 105—376)

The invention relates to railway refrigerator cars which are used to transport perishable commodities. Such cars are usually provided with a bulkhead to form an ice chamber separate from the lading compartment, and the object of the invention is to improve and strengthen the bulkhead and also to improve and strengthen the walls of the car adjacent the ice chamber and at the same time to provide relatively large vertical flues for the circulation of the convective air currents and at the same time obtaining a relatively large lading compartment of the car and ice chamber of the car.

Another object of the invention is to increase the size of the opening below the bulkhead by eliminating the usual posts which support the bulkhead and thereby obtain an uninterrupted space between the bulkhead and the floor of the car for air circulation.

Another object of the invention is to reinforce the bulkhead with a metallic plate so formed and positioned as to provide great strength to resist the horizontal thrust of the lading and the weaving of the car and at the same time provide a large flue area for movement of the circulating air in close proximity to the cooling or heating medium without decreasing the cubical capacity of either the lading compartment or ice chamber of the car.

Another object of the invention is to reinforce the end wall (and preferably also the side walls) of the ice chamber by a metallic plate so formed and positioned as to provide great strength to resist the horizontal thrusts of the shifting ice and also the impact blows of the ice as it enters the ice chamber and at the same time provide a large flue area for the movement of the circulating air in close proximity to the cooling or heating medium without decreasing the cubical capacity of the lading compartment or ice chamber of the car. The metallic plate is also positioned and attached to the car structure so as to resist the forces caused by the weaving of the car in motion and thereby maintain the structural elements in their proper relative position which not only lengthens the life of the car but preserves the heat resisting value of the insulation of the car. The construction is also adaptable to a car wherein the bulkhead is adjacent the side wall of the car or positioned near the middle of the car.

Another object is to provide means to brace the bulkhead against the wall reinforcing plate to obtain cooperation between these elements for mutual reinforcement.

Another object is to so form one of these means to support the ice grates of the ice chamber.

Another object is to form the wall (or bulkhead) reinforcing plate with a plurality of vertical corrugations and to provide apertures therein so that the spaces between the corrugations on both sides of the plate constitute flues for movement of circulating air while the corrugations constitute vertically disposed beams.

In the drawings:

Fig. 1 is a vertical section laterally of the car looking toward the bulkhead with the insulation and metallic reinforcing plate partially removed.

Fig. 2 is a vertical section laterally of the car through the bulkhead with the netting partially removed to show the metallic wall reinforcing plate.

Fig. 3 is a vertical section longitudinally of the car showing the relation of the end wall, bulkhead and associated parts.

Fig. 4 is a horizontal section between the floor and roof structure of the car showing the relation of the end wall, bulkhead and associated parts.

Figs. 5 to 9 inclusive show end portions of modified forms of the metallic wall reinforcing plate.

In the form of the invention illustrated the usual parts of the car are shown, such as center sills 2; side sills 3; floor stringers 4; floor boards 5; floor insulation 6; false floor 7; (or floor rack) 30 false floor support 8; ceiling 9; roof insulation 10; roof metallic sheets 11; carline caps 12; side plates 13; hatches 14; hatch lid 15; hatch plug 16; running boards 17; side posts 18; side sheathing 19; side lining 20; side insulation 21; corner posts 22; end lining 23; end sheathing 24; end insulation 25; end sill 26; end sill nailing piece 27 and end plate 28.

The bulkhead A is spaced apart from one wall of the car, usually the end wall B thereof, to provide an ice chamber C separate from the lading compartment D of the car. The bulkhead A is usually provided with openings adjacent the roof structure (40) and floor (41) respectively for air circulation between the ice chamber and lading compartment.

The ice chamber comprises an ice basket having foraminous vertical walls with vertical flues between the foraminous wall and the end wall B, side walls E and bulkhead A, respectively, to allow the circulating air to move adjacent the ice and be cooled thereby. The ice rests upon grates 43 at the lower part of the ice basket but spaced apart from the floor or drip pan 44 therebelow. The air being cooled by the ice in the

ice chamber falls by gravity through the flues, moves under the bulkhead and under the false floor, thence up through the lading and being warmed by contact with the lading rises to the 5 ceiling of the car and thence through the upper bulkhead opening into the ice chamber. This cycle is repeated continuously.

The ice is dropped into the ice basket through the hatches 14 and is broken up to augment melting, and due to this melting and also to the packing down of the ice while the car is moving, the 10 ice becomes quite compact and sometimes a crust is formed on the upper surface of the ice. Thus the air is prevented from moving through the 15 ice which therefore necessitates providing large flues around the ice basket; that is, between the ice basket and the end wall, side walls and bulkhead respectively.

One of the objects of my invention is to provide 20 a very strong bulkhead having large flues without materially decreasing the cubical capacity of the lading compartment or ice chamber. This is accomplished by providing a metallic plate 46 formed with a plurality of portions 47 in one plane 25 alternating with a plurality of portions 48 in another plane (see Fig. 4) which are connected by vertical webs 49 extending between the top and the bottom of the bulkhead; that is, from the upper part of the lower opening 41 to the lower 30 part of the upper opening 40. The foraminous wall 50 forming part of the ice basket is positioned adjacent the portions 48 of said metallic plate 46 in one of said planes and an insulated wall 51 is positioned adjacent the portions 47 of the plate 35 in the other of said planes. By so forming or corrugating a metallic reinforcing plate very strong vertical beams are provided to strengthen the bulkhead against the inertia force of the lading and at the same time vertical air flues 53—54 40 are provided on both sides of the reinforcing plate; in other words, all of the spaces between the vertical webs 49 constitute vertical flues.

The drawings show a removable insulated wall having lips 56 thereon which engage apertures 57 45 in the bulkhead reinforcing plate. (See Fig. 3.)

The bulkhead A is primarily supported by the strap 60 which preferably extends between the roof sheet (11) flanges 61 and is held in place by the rivets 62 which hold the roof sheet flanges 50 and carline cap 12 together. The bulkhead may also be partially supported by means (64) fastening it to the side walls E if desirable. By this 55 suspended bulkhead arrangement an uninterrupted space 41 between the bulkhead A and the floor of the car is provided for air circulation between the ice chamber C and lading compartment D. In the usual construction the bulkhead is supported by a plurality of posts (about four or five) which extend between the floor and roof 60 structure of the car and these posts interfere with the free circulation of air; or in other words, cut down the area of opening between the bottom of the bulkhead and the floor. In my construction I increase the area of this opening by supporting the bulkhead solely from the roof structure or solely from the roof structure and the side walls of the car.

The end wall B is preferably reinforced by a 70 metallic plate 70 formed with a plurality of portions 71 in one plane alternating with a plurality of portions 72 in another plane which are connected by vertical webs 73 extending between the roof structure and the underframe of the car and preferably secured thereto by the bolts 75 and 76 respectively whereby the reinforcing plate 70

constitutes a series of vertical beams to transmit any load imposed thereon to the roof structure and underframe. The portions 71 of the metallic plate in one of said planes is preferably positioned adjacent the end wall B of the car and a foraminous wall 77 is positioned adjacent the portions 72 of the plate in the other of said planes. The portions 72 of the metallic plate adjacent the foraminous wall 77 are provided with openings 79—80 to provide vertical air flues on both sides 10 of the reinforcing plate; in other words, with this arrangement all of the spaces between the vertical webs 73 constitute vertical air flues for the circulating air.

The side walls of the car forming part of the 15 ice chamber are also preferably strengthened by metallic reinforcing plates 81 formed in a similar manner to the end wall reinforcing plates heretofore described and arranged to perform the same functions thereof.

Figs. 5 to 9 inclusive show modifications of this 20 end wall reinforcing plate 70. In the construction shown in Fig. 5 the portions 82 adjacent the foraminous wall are cut away adjacent the ends of the plate to provide the openings 83.

Fig. 6 is a modification of Fig. 5 and shows the webs 86 tapered at their ends 87 and also shows the reinforcing plate secured to an attaching angle or member 88.

Fig. 7 shows the portions 90—91 in the spaced 25 apart planes merging into a common plane 92 thus forming terminal sloping portions which are provided with apertures 93 for the purposes described. The portion in the common plane 92 is bent to form an attaching flange 94 which is provided with apertures for bolts.

Fig. 8 shows a construction wherein the rear portions 95 merge into the plane of the front portions 96 and the plate is bent to form an attaching flange 97. The portions 96 in contact with 40 the foraminous wall are cut away to provide apertures or notches 98 for the purposes described.

In the drawings so far described I have shown flat portions of the metallic plate in spaced apart planes, but if desired, the plate may be formed in 45 to a plurality of corrugations of sinuous configuration, as shown in Fig. 9, which give better flue effect and also increased radiating surface. Corrugations of sinuous configuration, that is, where they are more rounded, minimize fatigue of metal 50 in the bending process and also minimize skin friction to air flow.

I preferably provide the upper brace 100 which receives the forces from the bulkhead A and distributes them to the side wall reinforcing plates 55 101 and to the end wall B. I also preferably provide a lower brace 103 which receives the forces from the lower part of the bulkhead and transmits them to the side wall reinforcing plates 81 and end wall reinforcing plate 70. This lower 60 brace 103 is also preferably provided to support the ice grates 43. In the construction shown the lower brace comprises a plurality of angles with one of the flanges 104 arranged to support the ice grate.

While ice is generally used in the "ice chamber" it is understood that a heater is sometimes used in this chamber to heat the circulating air and the lading.

By my arrangement the bulkhead, end wall and 70 side walls are reinforced by a substantial corrugated metallic plate, but at the same time the flue area for circulating air around the ice is not restricted, nor have I decreased the inside length of the lading compartment of the car.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car having a floor, a wall and a bulkhead spaced apart from the wall of the car to provide an ice chamber separate from the lading compartment, said bulkhead provided with openings adjacent the roof structure and floor respectively for air circulation between the chamber and the compartment, a reinforcing plate for said wall formed with a plurality of portions in one plane alternating with portions in another plane which are connected by a plurality of vertical webs whereby the reinforcing plate constitutes a series of vertical beams, the portions in one of said planes positioned adjacent said wall, and a foraminous wall positioned adjacent portions in the other of said planes, the portions of the plate adjacent the foraminous wall being provided with openings adjacent the opposite ends thereof to provide vertical air flues on both sides of the reinforcing plate. 5
2. In a refrigerator car having a roof structure, an underframe, a floor, a wall, and a bulkhead spaced apart from the wall of the car to provide an ice chamber separate from the lading compartment, said bulkhead provided with openings adjacent the roof structure and floor respectively for air circulation between the chamber and the compartment, a reinforcing plate for said wall extending between and secured to the underframe and roof structure, said plate formed with a plurality of portions in one plane alternating with portions in another plane which are connected by a plurality of vertical webs whereby the reinforcing plate constitutes a series of vertical beams, the portions in one of said planes positioned adjacent said wall, and a foraminous wall positioned adjacent portions in the other of said planes, the portions of the plate adjacent the foraminous wall being provided with openings adjacent the opposite ends thereof to provide vertical air flues on both sides of the reinforcing plate. 10
3. In a refrigerator car having a roof structure, a floor structure and a wall, a reinforcing plate for said wall extending between the floor structure and roof structure formed with a plurality of portions in one plane alternating with portions in another plane which are connected by a plurality of vertical webs said portions merging into a common plane adjacent said structures whereby the reinforcing plate constitutes a series of vertical beams between said structures, the portions in one of said planes positioned adjacent said wall, the portions of the plate in the other of said planes being provided with openings adjacent said structures to provide vertical air flues between the wall and the reinforcing plate. 15
4. A reinforcing plate for the wall of a refrigerator car formed with a plurality of portions in one plane alternating with portions in another plane which are connected by a plurality of vertical webs whereby the reinforcing plate constitutes a series of vertical beams, the portions of the plate in one of said planes being provided with openings adjacent the opposite ends thereof to provide vertical air flues on both sides of the reinforcing plate. 20
5. In a refrigerator car having a roof structure, an underframe, a wall, a reinforcing plate for said wall extending between and secured to the underframe and roof structure, said plate formed with a plurality of portions in one plane alternating with portions in another plane which are connected by a plurality of vertical webs whereby the reinforcing plate constitutes a series of vertical beams, the portions in one of said planes positioned adjacent said wall, and a foraminous wall positioned adjacent portions in the other of said planes, the portions of the plate adjacent the foraminous wall being cut away for the widths of such portions adjacent said floor and roof structure to provide vertical air flues on both sides of the reinforcing plate. 25
6. In a refrigerator car having a roof structure, an underframe, a wall, a reinforcing plate for said wall extending between and secured to the underframe and roof structure formed into a plurality of vertically positioned sinuous corrugations whereby the reinforcing plate constitutes a series of vertical beams, one side of the corrugated plate positioned adjacent said wall, and a foraminous wall secured to the other side of the corrugated plate, parts of the corrugated plate adjacent said floor and roof structure being perforated to provide vertical air flues on both sides of the reinforcing plate. 30
7. In a refrigerator car having a floor, a wall and a bulkhead spaced apart from the wall of the car to provide an ice chamber separate from the lading compartment, said bulkhead provided with openings adjacent the roof structure and floor respectively for air circulation between the chamber and the compartment, a reinforcing plate for said wall formed with a plurality of portions in one plane alternating with portions in another plane which are connected by a plurality of vertical webs whereby the reinforcing plate constitutes a series of vertical beams, the portions in one of said planes positioned adjacent said wall, and a foraminous wall positioned adjacent portions in the other of said planes, the portions of the plate adjacent the foraminous wall being provided with openings adjacent the opposite ends thereof to provide vertical air flues on both sides of the reinforcing plate, means to transmit horizontal forces against said bulkhead to said wall reinforcing plate. 35
8. In a refrigerator car having a floor, a wall and a bulkhead spaced apart from the wall of the car to provide an ice chamber separate from the lading compartment, said bulkhead provided with openings adjacent the roof structure and floor respectively for air circulation between the chamber and the compartment, a reinforcing plate for said wall formed with a plurality of portions in one plane alternating with portions in another plane which are connected by a plurality of vertical webs whereby the reinforcing plate constitutes a series of vertical beams, the portions in one of said planes positioned adjacent said wall, and a foraminous wall positioned adjacent portions in the other of said planes, the portions of the plate adjacent the foraminous wall being provided with openings adjacent the opposite ends thereof to provide vertical air flues on both sides of the reinforcing plate, means to transmit horizontal forces against said bulkhead to said wall reinforcing plate, one of said means constituting ice grate supports. 40
9. In a railway refrigerator car having a roof structure, an underframe and a wall, a metallic reinforcing plate for said wall formed with a plurality of vertical corrugations bearing against 45

- said wall and extending between the roof structure and underframe and secured thereto, said plate being provided with apertures to provide vertical air flues between the reinforcing plate and the wall.
- 5 10. In a railway refrigerator car having a roof structure, an underframe and a wall, a metallic reinforcing plate for said wall formed with a plurality of vertical corrugations bearing against said wall and extending between the roof structure and underframe, said corrugations merging into the plate adjacent the margins thereof which are bent to form attaching flanges, and means to secure said flanges to the roof structure and underframe, said plate being provided with apertures to provide vertical air flues between the reinforcing plate and the wall.
- 10 15. In a railway refrigerator car having a roof structure, an underframe, a wall, a vertically corrugated reinforcing plate extending between and secured to the roof structure and underframe with one side positioned adjacent said wall, an ice basket comprising a foraminous wall positioned adjacent the other side of the corrugated plate whereby the spaces between the corrugations adjacent the foraminous wall form flues for air circulation, said plate provided with apertures adjacent the roof structure and underframe respectively to establish air communication between the interior of the car and the spaces between the corrugations adjacent the car wall whereby the last mentioned spaces form flues for air circulation.
- 20 25. In a railway refrigerator car having a roof structure, an underframe and a wall; a metallic reinforcing plate for said wall formed with a plurality of vertical corrugations bearing against said wall and extending between the roof structure and underframe, said corrugations merging into the plate adjacent the margins thereof, and means to secure said plate to the roof structure and underframe, said plate being provided with apertures to provide vertical air flues between the reinforcing plate and the wall.
- 30 35. In a refrigerator car having a roof structure, a floor structure and a wall; a reinforcing plate for said wall extending between said structures and formed with a plurality of portions in one plane positioned adjacent said wall alternating with portions in another plane spaced apart from said wall, said portions being connected by vertical webs, said portions merging into common planes adjacent said structures whereby the reinforcing plate constitutes a series of vertical beams extending between said structures to reinforce said wall, the said portions that are spaced apart from the wall being provided with openings adjacent said structures to provide vertical air flues between the wall and the reinforcing plate.
- 40 45. In a refrigerator car having a roof structure, a floor structure and a wall; a reinforcing plate for said wall extending between said structures and formed with a plurality of portions in one plane positioned adjacent said wall alternating with portions in another plane spaced apart from said wall, said portions being connected by vertical webs whereby the reinforcing plate constitutes a series of vertical beams extending between said structures to reinforce said wall, the said portions that are spaced apart from the wall being notched to provide openings adjacent said structures to provide vertical air flues between the wall and the reinforcing plate, and an attaching member secured to the unnotched portions of the plate.
- 50 55. In a refrigerator car having a roof structure, a floor structure and a wall; a reinforcing plate for said wall extending between said structures and formed with a plurality of portions in one plane positioned adjacent said wall alternating with portions in another plane spaced apart from said wall, said portions being connected by vertical webs whereby the reinforcing plate constitutes a series of vertical beams extending between said structures to reinforce said wall, the said portions that are spaced apart from the wall being notched to provide openings adjacent said structures to provide vertical air flues between the wall and the reinforcing plate, the unnotched portions of the plate being bent to form attaching flanges.
- 60 65. In a refrigerator car having a roof structure, a floor structure and a wall; a reinforcing plate for said wall extending between said structures and formed with a plurality of portions in one plane positioned adjacent said wall alternating with portions in another plane spaced apart from said wall, said portions being connected by vertical webs, said portions merging into common planes adjacent said structures whereby the reinforcing plate constitutes a series of vertical beams extending between said structures to reinforce said wall, certain portions of the plate that are spaced apart from the wall being provided with openings adjacent said structures to provide vertical air flues between the wall and the reinforcing plate.
- 70 75. A wall plate for a railway refrigerator car formed with a plurality of portions in one plane alternating with portions in another plane connected by webs, said portions merging into common planes adjacent opposite margins of the plate, the portions in one of said planes being provided with openings adjacent the opposite ends thereof.
- 75 80. A wall plate for a railway refrigerator car formed with a plurality of portions in one plane alternating with portions in another plane connected by webs, the portions in one of said planes being notched to provide openings at the opposite ends thereof.

- ends thereof, and an attaching member secured to the unnotched portions of the plate.
21. A wall plate for a railway refrigerator car formed with a plurality of portions in one plane alternating with portions in another plane connected by webs, the portions in one of said planes being notched to provide openings at the opposite ends thereof.
22. A wall plate for a railway refrigerator car formed with a plurality of portions in one plane alternating with portions in another plane connected by webs, said portions merging into common planes adjacent opposite margins of the plate so as to form sloping terminal portions, said terminal portions having apertures therein.
23. In a refrigerator car having a roof structure, a floor structure and a wall; a reinforcing plate for said wall extending between said structures and formed with a plurality of portions in one plane positioned adjacent said wall alternating with portions in another plane spaced apart from said wall, said portions being connected by vertical webs whereby the reinforcing plate constitutes a series of vertical beams extending between said structures to reinforce said wall, certain portions of the plate that are spaced apart from the wall being provided with openings adjacent said structures to provide vertical air flues between the wall and the reinforcing plate.
24. In a refrigerator car having a roof structure, a floor structure, corner posts and a wall; a reinforcing plate for said wall extending between said structures and between said posts and secured thereto, said plate formed with a plurality of portions in one plane positioned adjacent said wall, alternating with portions in another plane spaced apart from said wall, said portions being connected by vertical webs whereby the reinforcing plate constitutes a series of vertical beams extending between said structures to reinforce said wall between said posts, certain portions of
- the plate that are spaced apart from the wall being provided with openings adjacent said structures to provide vertical air flues between the wall and the reinforcing plate.
25. In a refrigerator car having side walls, an end wall, a bulkhead, a vertically corrugated reinforcing plate positioned against each of said side walls and secured thereto, said corrugations having apertures therein to provide air flues between the plate and the adjacent wall, and a brace attached to the bulkhead and having normally extending end portions secured to the corrugations in the side wall reinforcing plates whereby forces against the bulkhead are distributed to the side wall reinforcing plates and the side walls.
26. In a refrigerator car having side walls, an end wall, a bulkhead, a vertically corrugated reinforcing plate positioned against each of said side and end walls and secured thereto, said corrugations having apertures therein to provide air flues between the plate and the adjacent wall, and a brace attached to the bulkhead and having normally extending end portions secured to the corrugations in the side wall reinforcing plates and also to the end wall reinforcing plate whereby forces against the bulkhead are distributed to the side and end wall reinforcing plates.
27. In a refrigerator car having side walls, an end wall, a bulkhead comprising a vertically corrugated metallic plate, a vertically corrugated reinforcing plate positioned against each of said side walls and secured thereto, said corrugations having apertures therein to provide air flues between the plate and the adjacent wall, and a brace attached to the corrugations in the bulkhead and having normally extending end portions secured to the corrugations in the side wall reinforcing plates whereby forces against the bulkhead are distributed to the side wall reinforcing plates and the side walls.

HORACE GIDDINGS.
